UNITED STATES PATENT OFFICE

152,930

DESIGN FOR A WASHING MACHINE

Clarence Gilbert Taylor, Alliance, Ohio

Application January 21, 1947, Serial No. 136,276

Term of patent 7 years

(Cl. D49—1)

To all whom it may concern:

Be it known that I, Clarence Gilbert Taylor, a citizen of the United States, residing at Alliance, in the county of Stark and State of Ohio, have invented a new, original, and ornamental Design for a Washing Machine, of which the following is a specification, reference being had to the accompanying drawing, forming part thereof.

Fig. 1 is a front elevation showing (in dotted lines) a washing machine or similar apparatus with the handles of the present design attached thereto.

Fig. 2 is a side elevation thereof.

Fig. 3 is a top plan view of the handle.

Fig. 4 is a fragmentary, front elevation of the upper portion of the handle.

The dominant features of my design reside in the portions shown in full lines.

I claim:

The ornamental design for a washing machine, as shown and described.

CLARENCE GILBERT TAYLOR.
